UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, LONDON, ENGLAND.

GUN-MOUNTING.

1,267,854.

Specification of Letters Patent. Patented May 28, 1918.

Application filed May 26, 1915. Serial No. 30,707.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Gun-Mountings, of which the following is a specification.

This invention relates to gun mountings of the casemate or upper deck type in which the elevating and training number or numbers are disposed within a shield moving with the gun in training.

According to this invention we so construct and arrange the casemate or upper deck mounting that the elevating and training number or numbers can be accommodated near the gun trunnions between the shield and downward extensions of the carriage cheeks, the space provided beneath the gun by the said extensions serving to receive the rack and pinion of the elevating mechanism so that the necessity for the side bar, which is usually provided in mountings of this kind, is avoided.

In order that the said invention may be clearly understood and readily carried into effect we will describe the same more fully with reference to the accompanying drawings, in which:—

Figures 1 and 2 are respectively a sectional rear elevation and a sectional side elevation showing one constructional form of the invention in connection with a twin gun mounting, and

Figs. 3 and 4 are views similar to Figs. 1 and 2 showing another constructional form of the invention.

In these figures A is the shield, B, B are the carriage side cheeks and B' is the center plate, the gun cradles C C being trunnioned in the side cheeks and the center plate. The side cheeks B, B are extended downwardly as aforesaid and they, together with the center plate are connected to or made integral with a ring or plate D which is rotatably supported by means of ball or roller bearings upon a bearing block D' carried by the deck as is well understood. The said ring is prevented from rising during the firing of the gun by a circular clip D² (or by several separate clips) attached to the bearing block D'. The gun cradles are pro-

vided with elevating racks C', C' situated in the spaces between the center plate B' and the downward extensions of the side cheeks B, B as is well understood and the two pinions C², C² engaging with these racks are operated by one elevating number so that the guns are elevated simultaneously. Instead of racks and pinions any other appropriate gearing may be used. The side cheeks carry seats or platforms c, c' for the elevating and training numbers respectively who are accommodated between the outer faces of the side cheeks and the shield A in such a position that the eye pieces of the sights can be arranged contiguous to the gun trunnions as shown.

In the construction shown by Figs. 1 and 2 the ring D is of angle cross section and roller and ball bearings are interposed in the usual manner between the bearing block and the vertical and horizontal portions respectively of the ring. If desired the vertical portion of the ring may be extended to form what may be termed a hollow training pivot.

In the construction shown by Figs. 3 and 4 the plate D carries a bearing d which engages with a center pivot d' projecting upwardly from the bearing block D' as has already been proposed. The said center pivot is of substantial diameter and may if desired be made hollow as shown.

What we claim and desire to secure by Letters Patent of the United States is:—

1. In a gun mounting, the combination with the shield and the gun carriage cheeks, of downward extensions of said cheeks, gun elevating means arranged centrally beneath the gun and between said downward extensions, and a handle arranged between one of the cheeks and the shield for operating said elevating means.

2. In a gun mounting, the combination with the shield and the gun carriage cheeks, of downward extensions of said cheeks, a gun elevating rack arranged centrally beneath the gun and between said downward extensions, a pinion gearing with said rack, and a handle arranged between one of the cheeks and the shield for operating said pinion.

3. In a gun mounting, the combination with the shield and the gun carriage cheeks, of downward extensions of said cheeks, a gun elevating rack arranged between said downward extensions, and a handle ar-

ranged contiguous to one of the gun trunnions between one of the cheeks and the shield for enabling the elevating number of the gun's crew to operate said elevating means while situated between one of the downward extensions and the shield.

4. In a gun mounting, the combination with the shield and the gun carriage cheeks, of downward extensions of said cheeks, a gun elevating rack arranged centrally beneath the gun and between said downward extensions, a pinion gearing with said rack, and a handle arranged contiguous to one of the gun trunnions between one of the cheeks and the shield for operating said pinion.

5. In a gun mounting, the combination with the shield, of gun carriage cheeks extending downward to the deck, gun elevating means arranged centrally beneath the

gun and between the downward extensions, a handle arranged between one of the cheeks and the shield for enabling the elevating number of the gun's crew to operate said elevating means while situated between one of the downward extensions and the shield, means for rotatably mounting said downward extensions on the deck, gun training means carried by one of said extensions and a handle arranged between one of the cheeks and the shield for enabling the training number of the gun's crew to operate said training means while situated between one of the downward extensions and the shield.

In testimony whereof we affix our signatures.

ARTHUR TREVOR DAWSON.
GEORGE THOMAS BUCKHAM.
